UNITED STATES PATENT OFFICE.

ALFRED F. C. LOTZ, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

RHEOSTAT.

Application filed March 26, 1925. Serial No. 18,523.

My invention relates to rheostats or resistance devices which are of particular utility in the radio field. Among the important objects of the invention are: to provide construction and arrangement which will permit easy and accurate relative movement between a contact member and a resistance element, but which will insure sufficient area of engagement of the resistance member to prevent sparking or heating; to provide for a substantially frictionless rolling engagement between the contact element and the resistance element to thus prevent wear of the elements, particularly the resistance element, so that the resistance value of said resistance element will remain constant; to provide construction and arrangement in which the contact and resistance elements are securely held together at all times in firm electrical engagement, yet will be easily operable; to provide construction and arrangement which will permit very accurate and reliable resistance adjustment to be made; and, in general, to produce a device which is simple in construction and arrangement, free from wear, and with which fine and dependable resistance adjustment can readily be made.

On the accompanying drawings, Fig. 1 is a rear elevational view of the rheostat device with the closure cover removed;

Fig. 2 is a sectional view on line 2—2 of Fig. 1;

Fig. 3 is a sectional view on line 3—3 of Fig. 1; and

Fig. 4 is a perspective view of the contact roller supporting spring frame.

A cylindrical cup or container 10 of insulating material, such as bakelite, houses the resistance controlling element and has a detachable cover 11 locked in place by bolt 12. Seating against the inner side of the cylindrical wall of the container is the resistance element 13, which is preferably in the form of a band or strip of suitable resistance metal or resistance composition. The ends of the resistance member are connected with terminal structures 14 and 15 mounted on the container wall, which terminal members may be the sole means for holding the resistance member in place, or additional securing means may be used. As shown, the ends of the resistance member

are securely anchored to the terminal structures and the member engages closely against the cylindrical wall of the container, which wall forms a backing therefor.

Extending axially from the base wall of the container 10 is an externally threaded sleeve 16 which is shown secured to the container by threading engagement and by means of the lock nut 17. The sleeve 16 journals the shaft 18, which, at its outer end, has the knob 19 by means of which the shaft 18 may be turned to operate the movable contact mechanism within the container. Within the container is a contact roller 20 connected with the shaft 18 by means of a spring frame F. This spring frame is formed from a single piece of sheet metal. It comprises a body part 21 from whose sides extend the parallel arms 22, 23 for receiving between them the contact roller 20, the shaft or axle 24 of this roller journaling in the holes 25 and 26 in the arms. The body is bent to form spring loops 27 and 28 and spring ends 29 and 30 parallel with the body 21, and from the diagonally opposite corners of the spring ends 29 and 30 extend the arms 31 and 32 which are parallel with each other and with the arms 22 and 23. The arms 31 and 32 have openings 33 receiving the reduced inner end 18' of the shaft 18, the frame being rigidly secured to the shaft end to rotate with the shaft. As shown, the shaft is flat on one side and the openings 33 are correspondingly flat, so that the frame will be non-rotatably held on the shaft. The frame is electrically connected with the terminal structure 34 on the container 10, the connection being by means of an L-shaped bar 35 having one end secured to the terminal 34 and the other end perforated to receive the shaft end 18' between the frame F and the shaft shoulder 36. The outer end of the shaft end 18' is threaded for receiving the nut 37, a spacer sleeve 38 being applied to the shaft end between the arms 31 and 32 of the frame, so that when the nut 37 is applied, the frame, the sleeve, and the bar 36 will be securely and electrically clamped to the shaft.

The contact roller 20 is of good electrical conductive material and is forced by the spring frame F toward the resistance element, but instead of having the roller engaged directly with the element, I interpose

- a contact ring or annular band 39 between the resistance element and the roller, this ring being of a diameter to insure adequate contact engagement with the resistance element. The ring is of good conductive material, such as copper, its extended area of engagement with the resistance element insuring more reliable contact and one of less resistance so that heating will be prevented. 5
- When the shaft 18 is turned, the frame F will swing around and will force the contact roller against the ring 39 and the ring 39 against the resistance element, the roller rolling along the inner face of the ring and the ring on its outer face rolling along the resistance element. Such rolling engagement practically eliminates friction, and consequently the roller and the ring, and particularly the resistance element will not 10 be worn away and the resistance element will therefore maintain its full resistance capacity and will not change, as is the case in devices where the frictional engagement will eventually wear down the resistance element and materially change its resistance properties. This frictionless rolling engagement and travel of the parts will permit the more accurate and easy rotation of the adjustment controlling knob 19. 15
- The spring walls 29 and 30, together with the spring loops 27 and 28, will maintain uniform and sufficient pressure against the contact roller to insure the proper pressure of the contact ring with the resistance element or material for the most efficient results. The cylindrical wall of the container 10 forms a rigid backing for the resistance material under such contact member pressure. The ring 39 surrounds the body of the spring F and engages between the arms 31 and 32 thereof. To assist the arms in holding the ring in proper alignment with the resistance material, the contact roller has the side flanges 40. 20
- The entire resistance device can be readily supported from a panel 41 by means of clamping nuts 42 and 43 engaging the sleeve 16. By means of the three terminals, the device may be used for ordinary resistance adjustment or as a potentiometer, and on account of the construction and arrangement described, very fine adjustment and regulation can be made and accurate and reliable results obtained. As changes and 25 modifications can be made which will so come within the scope of the invention, I do not desire to be limited to the precise construction and arrangement shown.
- I claim the following:—
1. In a resistance adjusting device, the combination of a circular resistance element, a circular contact member therefor of less diameter, a frame within said contact member journaled in the axis of said resistance element, a roller on said frame, said frame being of spring material and pressing said roller radially outwardly to cause said contact member to be held against said resistance element, said roller having rolling engagement with said contact member, and 70 said contact member having rolling engagement with said resistance element when said frame is revolved, and circuit terminals connected with said contact member and said resistance element. 75
2. In a resistance adjusting device, the combination of a cylindrical container, a resistance element supported against the inner face of said container concentric therewith, a shaft extending axially in said container, a frame fixed at one end to said shaft, a roller at the other end of said frame, said frame intermediate its ends being formed to produce spring pressure against said roller, and an annular contact member interposed 80 between said roller and resistance element, said roller having rolling engagement with said contact member and said contact member having rolling engagement with said resistance element when said frame is revolved, 85 and terminals on said frame connected with said contact member and resistance element. 90
3. In a resistance adjusting device, the combination of a container having a cylindrical wall, resistance material supported on 95 the inner side of said wall, a shaft extending axially in said container, a sheet metal frame secured at one end to said shaft, a roller journaled on the outer end of said frame, an annular contact member interposed between said roller and resistance material, said frame intermediate its end being bent to form a spring and exerting outward pressure against said roller, whereby said contact member will be clamped between said roller and resistance material, said roller having rolling engagement with said contact member, and said contact member having rolling engagement with said resistance material when said frame is 100 revolved. 105
4. In a resistance adjusting device, the combination of a container having a cylindrical wall, resistance material supported on the inner side of said wall, a frame, an axial shaft supporting said frame at one end, a roller journaled at the other end of said frame, a circular contact member interposed between said roller and resistance material, spring means on said frame acting against 115 said roller whereby said contact member is pressed against said resistance material, means on said roller for confining said contact member axially, and terminals connected with said contact member and resistance element, said roller having rolling engagement with said contact member and said contact member having rolling engagement with said resistance material when said frame is 120 revolved. 125

5. In a resistance device, a casing, a resistance member within said casing, a contact member urged toward the resistance member, said members being disposed in a common plane and having relative movement in said plane lengthwise of the resistance member, a second contact member confined between the first contact member and the resistance member, said first contact member travelling on the second contact member and pressing it against the resistance member, and means coacting with the two contact members for maintaining the second contact member in the plane of the first contact member and the resistance member and out of contact with the casing.
6. In a resistance device, a stationary resistance member, a contact member urged toward the resistance member and movable lengthwise thereof, a second contact member confined between the first contact member and the resistance member, the first contact member traveling on the second member and holding it in contact with the resistance member, and means carried by the first contact member confining the second contact member laterally and maintaining it in the plane of said first member and the resistance member.
7. In a resistance device, a stationary resistance member, a contact member urged toward the resistance member and movable lengthwise thereof, and a second contact member confined between the first contact member and the resistance member, said first contact member having lateral flanges confining the second contact member laterally and maintaining it in the plane of the first contact member and said resistance member, the first contact member travelling on the second contact member.
8. In a resistance device, an annular resistance member, a frame movable about an axis concentric with the resistance member, a roller carried by the frame and urged toward the resistance member, said roller having lateral peripheral flanges, and an annular contact ring disposed about the roller and confined between the flanges, said ring being held by the roller in contact with the resistance member.

In witness whereof, I hereunto subscribe my name this 23rd day of March, 1925.

ALFRED F. C. LOTZ.
